KEY LEVER ADJUSTING MECHANISM

James F. Koca, Woodstock, Ill., assignor to Woodstock Typewriter Company, Woodstock, Ill., a corporation of Illinois

Original application March 2, 1933, Serial No. 659,335. Divided and this application June 25, 1934, Serial No. 732,200

6 Claims. (Cl. 197—22)

This invention relates to typewriters in general, and specifically to means for regulating typewriter keys.

This application is a division of applicant's 5 copending application, Serial No. 659,335, filed March 2, 1933.

The primary object of the present invention is to provide means of a novel character for regulating the stroke of the typewriter key.

10 Another object of the invention is to provide novel means for regulating the movement or the length of stroke of the key levers of electrical- ly operated typewriters.

15 A still further object is to provide simple and efficient means to adjustably regulate the movement of the stroke of the key levers.

Numerous other objects and advantages will be apparent throughout the progress of the following specification.

20 The accompanying drawings illustrate a selected embodiment of the invention and the views therein are as follows:

25 Fig. 1 is a detail transverse sectional view of a typewriter showing means for regulating the movement of the key levers.

Fig. 2 is a detail elevation of some of the regulating mechanism shown in Fig. 1.

Fig. 3 is a detail plan section of the members shown in Fig. 2 on the line 3—3 of Fig. 1.

30 Fig. 4 is a detail perspective view of several of the parts shown in Figs. 1 to 3.

Fig. 5 is a view similar to Fig. 1 but showing a modification of the means for varying the depression of the key lever stroke.

35 Fig. 6 is a detail plan section on the line 6—6 of Fig. 5.

Fig. 7 is a detail perspective view of several of the parts comprising the depression stroke regulating means which are shown in Figs. 5 and 6.

40 The particular typewriter herein shown by way of illustration is a "Woodstock" typewriter and comprises a frame 10 upon which key levers 11 are arranged in the usual manner. The key levers 11 have their rear ends operatively supported by a transverse rod (not shown) which is removably supported in the sub-frame of the typewriter. Type bar actuators are controlled by the key levers 11 and operate the type bars 12 through the intermediary of sub-levers (not shown).

45 In electric typewriters, that is, in typewriters having type bars which are electrically actuated, the depression of the key lever to cause the rotating drive shaft to operate the type bars upon depression of a key lever, is relatively small or

short. However, operators who are used to the conventional type of machine where a long stroke is used, find it inconvenient, if not awkward, to become familiar with the new stroke. Also, operators of different speed require a different key lever stroke. Therefore, if the stroke of the key levers can be adjusted, the operators can quickly acclimate themselves to using electric typewriters. Also, the depression of the typewriter key lever can be adjusted to meet the demands of various operators having various strokes and speeds.

5 The means provided for changing or varying the distance the key levers travel vertically upon the depression of a key lever key comprises a longitudinal strip 13 made of any desirable material, but preferably sound deadening material, such as fiber. The strip 13 is provided with diagonal slots 14 which engage pins 15 projecting forwardly from a flange 16 of an angle member 17. The strip 13 is positioned between the flange 16 on the angle member 17 and a flange 18 on a supporting member 19 which is fixed to the main frame of the typewriter. The upper flange 20 of the member 17 abuts the underside of a flange 21 of the member 19. Screws 22 pass through elongated slots 23 in the member 17 and threadedly engage the threaded holes 24 as indicated at 25, Fig. 1. The member 17 is adapted for lateral slidable movement relative to the member 19. The member 17 is provided with a turned ear 26, Fig. 4 having a threaded opening 27 to receive the threaded end 28 of a thumb screw 29. The thumb screw 29 is revolvably mounted in the frame 19 as indicated at 30, Fig. 3. Pins 31 project inwardly from the inner face of the flange 18 of the support 19 and act as a guide for the strip 13. Upon rotation of the thumb screw 29, the angle member 17 can be moved to the right or left, and due to the pin and slot connection between the strip 13 and the member 17, the strip 13 will be caused to raise or lower depending upon the direction the screw 29 is rotated. The key levers 11 which rest upon the usual bottom rest, will then be located in vertical movement between the bottom rest and the bottom edge 32 of the strip 13. As the bottom rest is fixed, the key levers 11 will be limited in their vertical movement or travel by raising or lowering the strip 13, it being understood, of course, that the key levers 11 are normally spring-urged and as this spring-urging construction is well known in the art, no description thereof will be made herein. In accordance with the construction just described, the operator or typist, by merely op-

erating a thumb screw 29, may thus regulate or adjust the vertical movement of the type levers to suit his or her individual desire.

In Figs. 5 to 7 inclusive there is shown a modified arrangement of the parts for performing a similar operation. In these figures 40 designates a strip of sound deadening material, such as fiber. Pins 41 project from the strip 40 and are adapted to engage diagonal slots 42 formed in an intermediate member 43 and vertical slots 44 formed in the front flange 45 of a supporting member 46. The member 43 and the strip 40 are arranged between the front flange 45 and the rear flange 47 of the supporting member 46. The supporting member 46 is fixed to the flange 10 while the member 43 is adapted to have free lateral slidable movement relative to the supporting member.

The member 43 is provided with an inturned end 48 which is adapted to receive the threaded end 49 of a thumb screw 50. The thumb screw 50 has free revoluble movement relative to the frame 10 and is provided with a thumb piece 51 for rotating the screw. During rotative movement of the screw 50, the member 43 will be moved laterally and due to the slot and pin connection between the member 43 and the strip 40, the strip 40 will be forced to travel or be moved vertically, the slots 44 acting as guides for the strip 40.

The two parts, including the member 46, are fastened together in any suitable manner, such as by the screws 52. From the construction just described and clearly shown in Figs. 5 to 7 inclusive, it can be readily seen that vertical movement of the key levers 11 is restricted.

The invention provides improved efficient means of relatively simple construction for positively varying or regulating the vertical movement or the depression of the key levers, therefore permitting the operator or typist to adjust or regulate the stroke the desirable or preferred amount.

Changes may be made in the form, construction, and arrangement of the parts without departing from the spirit of the invention or sacrificing any of the advantages thereof, and the right is hereby reserved to make all such changes as fairly fall within the scope of the following claims.

50 The invention is hereby claimed as follows:

1. In a typewriter having a frame, pivotally mounted key levers having vertical movement, a supporting rest for the levers to limit the down-

ward movement of the levers, an upper rigid member above the levers, a sound deadening strip carried by the rigid member, means for shifting the rigid member laterally, and means associated with the rigid member and the strip for moving the strip vertically during lateral movement of the rigid member.

2. In a typewriter having a frame, pivotally mounted key levers having vertical movement, a supporting rest for the levers to limit the downward movement of the levers, an upper rigid member above the levers, a sound deadening strip carried by the rigid member, a revolably mounted member threadedly engaging the rigid member for moving the rigid member horizontally and a slot and pin connection between the rigid member and strip to move the strip vertically during horizontal movement of the rigid member.

3. In a typewriter having pivotally mounted key levers and a bottom rest for said key levers, a longitudinal bar above said key levers having its underside forming a stop for engagement with said key levers to limit the vertical movement of said key levers, and laterally slidable means engageable with said stop for moving said stop vertically.

4. In a typewriter having pivotally mounted key levers and a bottom rest for said key levers, a longitudinal bar above said key levers having its underside forming a stop for engagement with said key levers to limit the vertical movement of said key levers, laterally slidable means engageable with said stop for moving said stop vertically, and a thumb nut for shifting said means laterally.

5. A typewriter having a frame, key levers for said typewriter, spaced upper and lower stop elements above and below respectively of the key levers to limit the vertical movement of the key levers, a member adapted to be moved laterally and operatively connected to said upper stop element, and rotative means for moving said last named member laterally, lateral movement of said last named member causing vertical movement of the upper stop element.

6. In a typewriter having pivotally mounted key levers, an elongated bar engageable with the key levers for limiting the movement thereof, means including a plurality of pin and slot connections for bodily displacing said bar to uniformly vary the position of the bar with respect to the key levers, and a single control member for controlling said means.

JAMES F. KOCA.
